UNITED STATES PATENT OFFICE.

ERASTUS E. WINKLEY AND JOHN C. SMITH, OF LYNN, MASSACHUSETTS.

LASTING-MACHINE.

1,018,022.

Specification of Letters Patent. Patented Feb. 20, 1912.

Application filed April 20, 1908. Serial No. 427,972.

To all whom it may concern:

Be it known that we, ERASTUS E. WINKLEY and JOHN C. SMITH, citizens of the United States, residing at Lynn, in the county of Essex and State of Massachusetts, have invented certain new and useful Improvements in Lasting-Machines; and we do hereby declare the following to be a full, clear, and exact description of the invention, such as will enable others skilled in the art to which it appertains to make and use the same.

This invention relates to lasting machines, and more particularly to that type of lasting machine known as the "hand method" lasting machine.

When an upper is "pulled over", it is ordinarily secured at the center of the tip of the toe and at each side of the fore part about opposite the tip line. When so secured the fullness of upper between the points where it is secured bulges or bellies out and in lasting the shoe this portion of the upper is ordinarily taken care of by plaiting it over the insole. When the shoe is lasted by hand, or in what is known as the "bed" or "wiper" type of lasting machine, this plaiting of the fullness of the upper is accomplished by "wringing" the upper with a pair of hand lasting pincers. "Wringing" consists in seizing the margin of the upper with the pincers and while pulling rotating the pincer jaws to the right or left by a twist of the wrist. In wringing the upper a turning movement is imparted to the pincer jaws about an axis extending obliquely to the horizontal, or plane of the shoe bottom, and in the general direction of the pulling movement. It has been found in practice that a rotary or turning movement of the pincers about such an axis lays the margin of the upper snugly to the insole and produces the most effectual plaiting.

The object of the present invention is to provide mechanical means for laying the fulled portion of the upper to the last as effectively as it can be done by hand.

In accordance with this object one feature of the invention contemplates the provision in a machine of the general type specified, which already in the mechanical operation of its pincers closely follows the updraw and overdraw movements used in hand lasting, of mechanical means for imparting to the pincers, in addition, a turning movement for plaiting the fulled upper at

the toe, similar in its action on the upper, and in its effect, to hand wringing.

In the preferred embodiment of the invention the pincer jaws are mounted with their gripping faces at a substantial oblique angle to the horizontal and means is provided for rotating said jaws about an axis in the plane of said gripping faces or in a plane substantially parallel thereto. The turning movement thus takes place about an axis extending in the general direction of the overdraw movement, as in hand lasting. The plaiting movement thus mechanically imparted to the upper is similar in all respects to the plaiting movement obtained by hand manipulation of the pincers.

To the accomplishment of this object and such others as may hereinafter appear, as will be readily understood by those skilled in the art, the invention comprises the features and combinations of parts hereinafter described and particularly pointed out in the appended claims.

The various features of the invention will best be understood from a description of the preferred embodiment thereof illustrated in the accompanying drawing, in which the invention has been shown for purposes of description as applied to the type of hand method lasting machine exemplified by the United States Patents to S. W. Ladd and R. F. McFeely, No. 584,744, and S. W. Ladd No. 597,321.

In the drawings Figure 1 is a side elevation of a portion of a hand method lasting machine of the type above specified, with the improvement contemplated by the present invention applied thereto; Fig. 2 is a front elevation of the parts shown in Fig. 1; and Fig. 3 is a detail of the pincer jaws shown in Fig. 1, viewed in the direction indicated by the arrow *a* in Fig. 1.

In the illustrated embodiment of the invention, 2 is the bracket shown in the Ladd and McFeely patent above referred to as supporting the pincer jaws, which, by the mechanisms described in the patent, have imparted to them the movements necessary to place an upper in overworked position on a last, viz: the pulling or updraw movement, the outward or overdraw movement, and the sidewise or transverse movement used with a rotary movement for plaiting the upper around the toe. In the present invention, instead of mounting the pincer jaws directly in this bracket as in the patent,

a sleeve 4, depending from the pincer lifting lever 28 and passing through the bracket, supports an auxiliary bracket 6 which in turn sustains a carrier 8 for the pincer jaws. This carrier 8 extends at an oblique angle to the horizontal, the direction being upwardly and outwardly from the plane of the front of the machine and in the general direction of the pull in over-drawing the upper. Within the carrier 8 is rotatably journaled the shank 10 of the pincer jaws. These pincer jaws may be constructed in a variety of ways, but as herein shown the lower jaw 12 is conveniently formed integral with the shank 10 and has pivotally mounted upon it the upper jaw 14, the two jaws being normally maintained open by means of a small coiled spring 16 mounted upon a pin 18 carried between the jaws and back of their gripping faces. In order to close the jaws against the force of the spring 16 there is utilized a plunger 20 which is mounted for vertical sliding movement within the sleeve 4 and corresponds to the rod or plunger for closing the movable gripper jaw in the Ladd and McFeely patent hereinbefore referred to. This plunger 20 bears upon the upper jaw 14 and is carried downwardly, to close the jaws, by means of a cam, and upwardly, to permit the jaws to open under the force of the spring 16, by means of a spring, in the manner fully described in said Ladd and McFeely patent. Thus the pincer jaws of this invention, although differently mounted from what is shown in the United States patents referred to, are opened and closed by a mechanism similar to that employed in said patents.

As is well known to those skilled in the art, for the most complete and effective manipulation of the upper, and particularly in lasting the toe, the pincers should be turned as well as moved sidewise or transversely in order to plait and lay the fullness of the upper at this part of the shoe snugly to the insole. To this end means is provided for imparting a rotary movement to the pincer jaws in addition to the transverse movement.

The mechanism for moving the pincers transversely may be and is similar in all respects to that shown in the patent to Ladd and McFeely heretofore referred to. In that patent this mechanism for moving the pincers transversely is also utilized to impart a rotary movement to the pincers about an axis comprised by the vertically arranged rod for closing the jaws, which corresponds to the rod or plunger 20 herein described.

This is accomplished in the patented construction by means of a gear on the rod and a transversely movable rack which engages therewith and is given a reciprocatory movement from the mechanism for moving the pincers transversely. It has been found ex-

pedient in the present instance to utilize this reciprocating member in imparting the desired rotary movement to the pincer jaws herein described. This bar is shown at 22 and is formed with plane surfaces, thus acting merely as a guide bar or actuator guided in suitable ways 23. To the left hand end of this slide there is pivoted one arm 24 of a bell crank lever journaled on a stud 26 mounted in brackets on the lever 28 which imparts the vertical movement to the pincer jaws. To the other arm 30 of this bell crank lever there is pivoted a short link 32 which in turn is universally connected, as at 34, to the inner end of a lever 36, also pivoted upon the pincer lifting lever 28. The outer end of the lever 36 has connected thereto, also by a universal joint 38, the upper end of a link or rod 40, the lower end of which is pivoted to the outer end of a crank arm 42. The crank arm 42 is journaled upon a stud 44 mounted in the auxiliary bracket 6, and this crank arm has connected thereto a toothed segment 46, also journaled upon the stud 44. The segment 46 is adapted to intermesh with a second segment 48 on the outer end of the shank 10 of the pincer jaws, which, as before stated, is journaled in the obliquely mounted carrier 8. With such a construction as that just described, it is seen that when the pincers are moved transversely, by the mechanism described in the Ladd and McFeely patent, the bell crank 24-30 is rocked about its pivot 26, which in turn imparts a rotary motion to the segment 46, thereby rotating the segment 48 and the shank 10 of the pincer jaws which imparts the desired turning movement to the said jaws. In order to maintain a constant engagement between the pincer jaws and the jaw closing plunger 20 during the turning movement, one of said parts, as illustrated the upper jaw 14, is provided with a bearing surface 50 formed in the present embodiment of the invention as an arc-shaped bar of sufficient length to allow for the oscillations of the pincer jaws.

It will be noted that when the pincer jaws are in gripping position they are maintained by the pincer carrier at a substantial oblique angle to the horizontal, the angle being of such amplitude that, when the pincers are moved downward toward the sole to grip the margin of the upper, their jaws will extend in planes at each side of the upper as it projects above the last bottom. While the described angle of the pincer carrier is not a fixed oblique angle, except during the updraw movement, because the forward swing of the pincer carrier bracket during the overdraw movement will necessarily alter the angle of the shank of the pincers to the horizontal, such movement, as will be apparent to those skilled in the art, is never sufficient to change the angle 130

from an oblique angle. In other words, the construction is such that the pincer jaws are supported at an angle permanently oblique to the horizontal, or plane of the shoe bottom, throughout the lasting operation. This is believed to be an important feature of the present invention as it has been found in practice to assist in the difficult work of shaping the upper to the last, particularly at 10 the toe.

In the following claims, all reference to position or direction of movement of the elements are to be interpreted as terms of designation, and not of limitation, as obviously it is the relative position or relative direction of movement which is alone of importance.

Nothing herein contained is to be construed as limiting the invention in the scope 20 of its application to use in connection with the particular machine or particular mode of operation, or both, selected for purposes of illustration and explanation. While the particulars of construction herein set forth 25 are well suited to one form of the invention, it is not to be understood that these particulars are essential, since they may be variously modified within the skill of the artisan, without departing from the true scope of the 30 actual invention as defined in the following claims.

What is claimed as new, is:—

1. In a lasting machine, pincer jaws for seizing the stock arranged with their gripping faces in a plane at an oblique angle to the horizontal, in combination with means for moving said pincer jaws transversely in said plane and for rotating said jaws about an axis in or substantially parallel to said 40 plane to plait the stock.

2. In a lasting machine, pincer jaws for placing an upper in over-worked position, a pincer carrier for rotatably supporting the pincer jaws at an angle permanently oblique to the plane of the shoe bottom throughout the lasting operation, and means for imparting a turning movement to the pincer jaws within the carrier.

3. In a lasting machine, a pincer jaw carrier extending at an angle permanently oblique to the horizontal, pincer jaws for seizing the stock rotatably sustained in said carrier, mechanism to impart a lasting movement to said jaws, and means controlled by said mechanism to rotate said jaws to plait the stock.

4. In a lasting machine, a pincer jaw carrier extending at an angle permanently oblique to the horizontal, pincer jaws for seizing the stock mounted on a shank journaled within said carrier, a gear on said jaw shank, a second gear meshing therewith, and means to oscillate said second gear to impart a turning movement to said jaws.

5. In a lasting machine, normally open

pincer jaws for placing an upper in over-worked position on a last, a plunger engaging one of said jaws, means to reciprocate said plunger to close the jaws, means to impart a turning movement to said jaws about an axis extending obliquely to the horizontal, and an extended bearing surface on one of said parts for maintaining a constant engagement between the jaws and plunger during the turning movement.

6. In a lasting machine, pincer jaws for seizing the stock arranged, when in gripping position, with their gripping faces in a plane at an oblique angle to the shoe bottom, and means for rotating said pincer jaws about an axis in or substantially parallel to said plane to plait the stock, said axis being permanently oblique to the shoe bottom throughout the movement of the pincers.

7. In a lasting machine, pincer jaws, means for actuating said jaws to pull the stock approximately perpendicularly to the plane of the shoe bottom, and means for rotating said jaws about an axis at a substantial angle permanently oblique to the pulling movement to plait the stock.

8. In a lasting machine, pincers having a shank extending at a substantial angle permanently oblique to the horizontal, jaws on said shank having their gripping faces in alinement therewith, and means for imparting a turning movement to the jaws about the shank of the pincers as an axis.

9. In a lasting machine, pincer jaws for seizing the stock, means for imparting an overdraw movement to said jaws, means for moving the jaws transversely during the overdraw movement, and means for rotating said jaws about an axis extending in the general direction of the overdraw movement.

10. In a lasting machine, pincer jaws movable approximately perpendicularly to the shoe bottom to pull the stock, a pincer carrier for supporting said pincers with the plane of their gripping faces at such time at a fixed substantial oblique angle to the plane of perpendicular pincer movement the line of intersection between said planes being substantially horizontal, and means to plait the stock by constantly changing the direction of the line of intersection between said planes while permanently maintaining the pincer carrier in an oblique angular position.

11. In a lasting machine, pincer jaws for seizing the stock, a pincer jaw closing rod, actuating means therefor, and means for rotating said pincers about an axis extending at an angle to said rod.

12. A shoe lasting machine, having, in combination, grippers mounted for rotation about an axis parallel with the gripping faces of the gripper jaws and passing between them, said axis being inclined to the

plane of the shoe bottom at an axis of approximately 45 degrees.

13. A shoe lasting machine, having, in combination, grippers mounted for rotation about an axis parallel with the gripping faces of the gripper jaws and passing between them, said axis being inclined from the plane of the shoe bottom, and means for moving the grippers in the general direction 10 of the axis of the grippers to overdraw the shoe upper.

14. In a lasting machine, the combination with pincers and means including a shoe rest for determining the plane in which the 15 shoe bottom shall be presented, of mechanism for rotating the pincers about an axis oblique to the plane of the shoe bottom to plait the upper and means adapted to be ad-

justed while the machine is in operation for varying the extent of the rotary movement. 20

15. In a lasting machine, pincer jaws for seizing the stock arranged, when in gripping position, with their gripping faces in a plane at an oblique angle to the horizontal, and means for rotating said pincer jaws 25 about an axis passing between the jaws, and in the plane of their gripping faces when the jaws are closed, to plait the stock.

In testimony whereof we affix our signatures, in presence of two witness.
